UNITED STATES PATENT OFFICE

JAMES T. LIGHTFOOT, OF MERCED, CALIFORNIA

AIRPLANE PROPELLER

Application filed August 1, 1930. Serial No. 472,250.

This invention relates to airplanes, and particularly to the propulsive means thereof. The principal objects of my invention are to provide a propeller of such form that it has a better hold on the air than the ordinary type; one with which a higher speed of the plane with a lower engine speed and propeller speed may be attained, so that vibration and noise are minimized; and a propeller arrangement which is so mounted on the airplane that the plane will have a very steady gliding movement through the air.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a top plan view of an airplane of the monoplane type, as equipped with my propeller arrangement.

Fig. 2 is a longitudinal edge view of a propeller.

Fig. 3 is a cross section of the propeller on the line 3—3 of Fig. 2.

Referring now more particularly to the characters of reference on the drawings, the airplane as shown may be one of a standard type comprising essentially a fuselage 1 having a wing 2 projecting laterally from the same adjacent its forward end, and substantially on the same level as the fuselage, as is the common practice in monoplane construction. My improved propeller arrangement which is mounted in connection with such airplane consists essentially of two propeller units, which are disposed rearwardly of the wing to the sides of the fuselage.

Each such unit comprises a shaft 3 extending lengthwise of the airplane and laterally spaced relative to the fuselage. This shaft is journaled in end bearings 4, the forward one of which is mounted in connection with the back edge of the wing, while the rear one is mounted on a laterally extending spar 5

secured to the fuselage. Fixed on the shaft at suitable longitudinally spaced points intermediate the bearings are spider units, each comprising rigid radially extending and opposed arms 6 to the outer ends of which the blades or vanes 7 of the propeller are fixed.

These blades are of substantially rectangular form and are of such length as to extend nearly the full distance between the wing and the spar. The blades however are somewhat wider at the rear than at the front, and since their inner edges are preferably parallel to each other and to the shaft, the outer edges of said blades diverge from each other toward the rear end and relative to the plane of the shaft. The blades may be made of sheet metal or the like of substantially even thickness throughout and are bent or otherwise formed with a considerable curvature as at 8 which extends for their full length toward their outer edges. This curvature is concave relative to the direction of rotation of the propeller, as indicated in Fig. 3. The spider or arm units are disposed in different radial relation to each other on the shaft so that the blades, which are actually straight from end to end will be disposed at a certain pitch relative to the axial plane of the shaft as shown in Fig. 2.

The shafts of the two propeller units are adapted to be rotated at the same speed and in opposite directions, or so that the blades when uppermost turn away from each other, by any suitable means. In the present instance such means is shown as being a transverse shaft 9 mounted on the wing and connected to the adjacent ends of the shafts 3 by bevel gearing 10. The shaft 9 in turn is geared as at 11 to a gas engine 12 or other power plant mounted in the fuselage.

By means of this construction and due to the direction of rotation of the propellers relative to the concavity of the blades, the air is engaged for the full length thereof.

Since the blades are disposed at an angle or pitch to their shafts and to the line of travel of the airplane, they have an auger-like action in the air, forcing the air rearwardly with a subsequent forward propulsion of the airplane. Since the width of the blades, or

the diameter of the propellers as a whole is somewhat greater at the rear than at their forward ends, the air as thrown rearwardly and centrifugally by the action of the forward portions of the blades, will not clear the rear portions of the blades as quickly as would otherwise be the case. Some of this centrifugally thrown air therefore remains engaged with or is reengaged by the blades 5 toward their rear ends, which aids in the propulsive effort of the propellers.

As a result of the particular form of the propeller and of the relation of the propellers to each other and to the fuselage, an ordinary 10 gliding movement is imparted to the airplane and the craft may travel at a high speed, with a relatively slow speed of rotation of the propellers and engine, and with a consequent minimum of vibration. Such movement of 15 the airplane is thus had partly on account of the counterbalancing effect of the opposed propellers, and partly because of the relatively great volumes of the air constantly engaged by such propellers. The propellers being in substantial horizontal alinement with 20 the fuselage, the sides of the latter catch air thrown centrifugally from the adjacent blades of the propellers, and such air tends to hold the airplane steady on account of the opposed and balancing pressure which it exerts 25 against the fuselage.

Though I have here shown and described 30 the propellers as only having a pair of opposed blades, it is of course to be understood that the number of blades may be increased if desired without affecting the principle of 35 operation of the structure.

From the foregoing description it will be 40 readily seen that I have produced such a device as substantially fulfills the objects of the invention as set forth herein.

While this specification sets forth in detail 45 the present and preferred construction of the device, still in practice such deviations from such detail may be resorted to as do not form a departure from the spirit of the invention, as defined by the appended claims.

Having thus described my invention what 50 I claim as new and useful and desire to secure by Letters Patent is:

1. A propeller comprising a shaft, and opposed blades extending lengthwise of the shaft and mounted in connection therewith in substantially radial relation thereto; said 55 blades from end to end being disposed at a constant angle to the axial plane of the shaft.
2. A propeller for an aircraft or the like comprising a shaft, and blades extending lengthwise of the shaft in opposed and substantially parallel relation to each other but set at an angle to the axial plane of the shaft; the outer portions of the blades being formed 60 for their full length with a concave curvature relative to the direction of rotation of the 65 propeller.

3. A propeller as in claim 2, in which the outer edges of the blades diverge at a slight angle relative to each other from front to rear whereby the propeller is of greater diameter at the rear than at the front. 70

4. A propeller comprising a shaft, and opposed straight edged blades extending lengthwise of the shaft, the blades being straight from end to end in their longitudinal planes and set at an acute angle to the axial plane of the shaft, and having also a transverse twist whereby their outer and inner longitudinal edges are disposed at different angles to the axial plane of the shaft. 75

In testimony whereof I affix my signature. 80
JAMES T. LIGHTFOOT.
